RADIO RECEIVING SYSTEM

Yves Rocard, Paris, France, assignor to La Radio-
technique, Paris, France, a corporation of
France

Application January 15, 1932, Serial No. 586,768
In France January 22, 1931

5 Claims. (Cl. 250—20)

This invention relates to a radio-receiving apparatus having frequency change characteristics and a separate oscillator and the invention renders possible the regulations of the circuit tuned to the frequency received and of the heterodyne circuit 5 totally independent of one another in a frequency changing system, as for example, in a superheterodyne radiotelephonic receiver. The invention may be carried out by various means of which a non-restrictive example will be given. The principal 10 effect obtained by the invention is the elimination of the "blank spots" which these receivers always present in the range of received frequencies, and the invention makes it possible for the single control of the tunings of the circuits to be effected in 15 a simple and practical manner.

In the case of a superheterodyne receiver embodying a separate oscillator, it will be appreciated that there exists a coupling between the circuit tuned to the frequency to be received, and that traversed by the frequency of the heterodyne, and in particular by the parts which conduct the two frequency currents into the tube which is arranged to effect the detection of the intermediate frequency. For example this tube 20 will have its grid connected to a circuit tuned to the frequency of the wave to be received, and the impedance of this tuned circuit will be coupled to a coil forming a part of the circuit tuned to the heterodyne; and such a coupling is sufficient to 25 make the regulations of the tuned circuit and of the heterodyne interdependent, and to prohibit the possibility of employing a strictly single control.

As a matter of fact, the input circuit of the control grid of the tube which is arranged to detect the mean or intermediate frequency, is generally tuned by a condenser. This resonant circuit is thus shunted by the capacities formed between 30 the control grid and the cathode and between the control grid and the plate of the tube, each being in series with the impedance in the circuit of the corresponding electrode. It will be understood that if this grid-cathode or grid-plate capacity 35 comes into resonance-series with the charge impedance in question (which will be for example the oscillating circuit of the heterodyne), the aforesaid input circuit will be shunted by a resulting zero impedance; at the frequency for which this 40 is produced there will be no signal impressed upon the grid, and the receiver will have a "blank spot" at this particular wave frequency. If recourse is taken to changing the beat by manipulating the heterodyne, this effect may be avoided, but there 45 is then produced an effect which is quite as unde-

sirable, namely, the tuned circuit is placed in resonance-series by the capacity existing between the grid and the other electrodes and short-circuits the oscillating circuit of the heterodyne.

Now with the inherent capacities between electrodes which are present in the tubes, with the order of the mean frequencies employed, these phenomena are produced actually in the scale of broadcast frequencies and they are only avoided by using the second or third harmonic of the 10 heterodyne, a procedure which cannot usually be employed over the whole scale without inconveniences, as the fundamental of the heterodyne will sometimes be very close to the mean frequency, and, furthermore, the amplitude of the 15 harmonics in question varies considerably over the scale of frequencies.

In addition to the serious disadvantages above described, this interdependence or mutual reaction of the circuits always introduces a mutual 20 dependence of the regulations of the two circuits, which undesirable coupling by its tendency to capricious variation over the scale of frequencies and variation from one tube to another, makes the employment of a single control practically 25 impossible. In other words, with the undesirable coupling present between circuits of different frequency as in the case of known superheterodyne receiving circuits, when two aligned condensers are adjusted to their most favorable position for 30 a predetermined frequency, if then the two condensers are simultaneously turned in order to obtain another frequency, it would be possible to obtain the most favorable position of only one of these condensers, for the second condenser could 35 not be properly set by the same control, even if it varies in accordance with the same law as in the case of the former condenser. This divergence will vary to the greatest extent if the tube involved is replaced by another one of slightly different 40 characteristics.

The present invention makes the regulations of the circuits tuned to the wave to be received independent of the regulation of the heterodyne, and conversely. By this, it is meant that the position of the variable member (for example, a variable condenser) which tunes the receiving circuit to a carrier wave, is independent whatever 45 may be the value given to the frequency of the heterodyne. It is established that the tunings to the carrier wave and the heterodyne follow simple and regular laws as a function of the capacities, for example, variable, which renders it possible 50 for a single control to be employed.

The present invention provides a means for insulating the circuit tuned to the wave frequency to be received from that arranged to be traversed by the frequency current of the heterodyne and which solves the problem resulting from the inconveniences of the system above described. More particularly the present invention provides a variation means for carrying out the same general idea which is explained in my co-pending 10 United States patent application, Serial No. 586,767, filed January 15, 1932.

The invention will now be described with reference to the annexed drawing in which Figures 1 and 3 represent superheterodyne circuits employing a separate oscillator and arranged in accordance with the invention, and Figure 2 illustrates a modified circuit detail applicable to each of the circuits illustrated in Figures 1 and 3.

The essence of the invention consists in conducting the two oscillatory currents, namely, that of the receiving circuit and that of the heterodyne to the grid of the tube of a superheterodyne receiver which produces the intermediate frequency, by means which, from all practical consideration, produce no coupling between the two tuned circuits. As an example of means which attain this result there is provided a high resistance potentiometer, for example of 250,000 ohms, of which the two extremities are connected one 20 to the output of the circuit tuned to the wave to be received, and the other to the output of the circuit of the heterodyne, or to a point of oscillating potential of this circuit. The intermediate point of the potentiometer is connected to the 25 grid of the tube producing the intermediate frequency so that, for example, 50,000 ohms of the potentiometer are located on the side of the circuit tuned to the wave to be received and 200,000 ohms thereof on the side of the heterodyne.

30 This arrangement is primarily illustrated in Figure 1 in which an aerial 1 is connected through a small capacity C_0 to a tuning circuit $L_1 C_1$ connected to the grid of a screened grid high frequency amplifying tube 2. In the plate circuit 35 of the tube 2 a shock impedance ch is inserted, and a large capacity C' is arranged in shunt to feed a tuning circuit $L_2 C_2$. This latter circuit is connected through a resistance r which may be 40 of, for example, 50,000 ohms to the grid of the tube 3 producing the intermediate frequency and which is followed by an intermediate frequency filter 5. The oscillating circuit $C_3 L_3$ of an oscillating tube 4 is connected to the grid of the tube 50 although other arrangements are possible, and is also connected to the grid of the tube 3 through a resistance R , the value of which is, for example, 200,000 ohms.

The operation of the apparatus is as follows: 60 Let Z be the impedance of the circuit $L_2 C_2$ for the frequency of the heterodyne. At the terminals of the circuit $L_3 C_3$, an oscillation of 20 volts will generally be produced, of which the 65 fraction:

$$\frac{r+Z}{R+r+Z}$$

70 will alone be transmitted to the grid of the tube 3. This fraction amounts to about 4 volts which is amply sufficient for the tube 3 to give a good detection by means of the plate. On the other hand, if Z_1 be the impedance offered by the circuit $L_3 C_3$ and its couplings for the frequency of

the wave received, it will be represented by the fraction:

$$\frac{R+Z_1}{r+R+Z_1}$$

5 of the volts at the terminals of the circuit $L_2 C_2$ which will be transmitted to the grid of the tube 3. With the values of r and R above indicated, this fraction will be of the order of about $\frac{1}{5}$ which means that this method of coupling will 10 only have caused the loss of $\frac{1}{5}$ th of the amplification. It will furthermore be appreciated that as the two circuits $L_2 C_2$, $L_3 C_3$ are only connected through the high resistance $r+R$, this high resistance coupling does not introduce any reciprocal dependence between the regulations of the 15 two circuits and the object of the invention is thus fully attained by the described arrangement.

In regard to the selection of the proper values for the resistances r and R , it is advisable to 20 make r and R as large as possible whilst R/r remains large. But this is not exact on account of the existence of a certain capacity C' between the grid of the tube 3 and earth and which will 25 ordinarily be of the order of 10 cm. If it is desired that the arrangement described should act correctly without too much loss of amplification 30 of the signal wave received, it is at least necessary that r remains small as compared with the leakage impedance

$$\frac{1}{C' \omega}$$

offered by the capacity C' , ω representing the 35 cycles.

As this impedance is particularly small when ω , representing the frequency, increases, that is to say, with short waves, the invention provides that the resistances r and R may be variable, or more simply, that the total resistance $r+R$ is 40 constituted by a potentiometer, the variable point of which is connected to the grid of the tube 3, and in this way r and R may be best adjusted, and in particular r be made equal to zero for short wave reception, in which case the whole 45 of the voltage of the received frequency would be delivered to the grid of the tube 3 and only the fraction

$$\frac{Z}{R+Z}$$

50 of the volts of the heterodyne. This naturally requires that Z shall be fairly large, which is the case for the range of wave lengths of 200 meters-600 meters, and a mean frequency of the order of 60,000 cycles. On the contrary, with a range of wave lengths of from 1000 meters to 2000 meters Z would equal 2000 ohms only, with the usual values of the impedances and tuning 55 capacities, in which case

$$\frac{Z}{R+Z}$$

60 becomes too small a fraction; it is then essential to re-introduce the resistance r .

65 Instead of using a variable potentiometer, the resistances r and R can be combined in the form of a potentiometric single resistance $r+R$ as indicated in Figure 2. Tapped points of this resistance are connected to points over which the handle of the switch connected to the grid of the tube 3 slides in the manner of the variable slide of Figure 1. A combination Z , R may also be 70 provided for the short waves and another for the long waves, the passage from one to the other 75

being effected by means of a selector switch as shown in Figure 2.

It will also be appreciated that the manipulation of the potentiometer above mentioned, also constitutes a volume control, but this volume control nevertheless does not render it possible for the intensity to be reduced absolutely to zero. It may be completed by introducing in shunt between the grid of the tube 3 and earth, a variable resistance R_1 , as shown in Figure 3, which may be reduced to zero and of which the maximum values should be very high, of the order of 10^6 ohms, so as not to diminish the efficiency of the arrangement when it is necessary that it should possess a maximum sensitiveness.

What I claim is:

1. In a radio receiver of the heterodyne type, the combination of a circuit arranged to be traversed by the radio frequency currents received and having a terminal subjected to a predetermined radio frequency potential with respect to the earth, a generator of oscillations of inaudible frequency having an output circuit, a connection comprising a high ohmic resistance between the output circuit of the said generator and said terminal of the said first-named circuit, a tube having a plurality of electrodes, one of which is an input electrode and a conductive connection between the input electrode of the said tube and an intermediate point on the said resistance.

2. In a radio receiver of the heterodyne type, the combination of a circuit arranged to be traversed by the radio frequency currents received and having a terminal subjected to a predetermined radio frequency potential with respect to the earth, a generator of oscillations of inaudible frequency having an output circuit, a connection comprising a high ohmic resistance between the output circuit of the generator and said terminal of the said first-named circuit, a tube having a plurality of electrodes, one of which is an input electrode, a conductive connection between the input electrode of the said tube and an intermediate point on the said resistance and means operable to vary the position of the said point between the ends of the resistance.

3. In a radio receiver of the heterodyne type, the combination of a circuit arranged to be trav-

ersed by the radio frequency currents received and having a terminal subjected to a predetermined radio frequency potential with respect to the earth, a generator of oscillations of inaudible frequency having an output circuit, a connection comprising a high ohmic resistance between the output circuit of the said generator and said terminal of the said first-named circuit, a tube having a plurality of electrodes including a control grid, one of which is an input electrode and a conductive connection between the said grid and an intermediate point on the said resistance.

4. In a radio receiver of the heterodyne type, the combination of a circuit arranged to be traversed by the radio frequency currents received and having a terminal subjected to a predetermined radio frequency potential with respect to the earth, a generator of oscillations of inaudible frequency having an output circuit, a connection comprising a high ohmic resistance between the output circuit of the said generator and said terminal of the said first-named circuit, a tube having a plurality of electrodes including a control grid, one of which electrodes is an input electrode, a conductive connection between the said grid and an intermediate point on the said resistance, and a variable ohmic resistance interposed between the said point and earth.

5. In a radio receiver of the heterodyne type, the combination, with a tube having a plurality of electrodes, one of which electrodes is an input electrode, of an input circuit connected to the control grid of said tube and arranged to be traversed by the radio frequency currents received by said receiver, an oscillation generator having an output circuit and being connected to the connection between the input circuit and the control grid of the said tube in order to produce a different frequency in the output circuit of said tube, an ohmic resistance inserted in the connection between the output circuit of the oscillation generator and the control grid of the said tube, and a second ohmic resistance interposed between the output of the said input circuit and a point of the first mentioned ohmic resistance connected to the control grid of said tube.

YVES ROCARD.
